STAPLING MACHINE

William G. Pankonin, Chicago, Ill.

Application December 12, 1932, Serial No. 646,847

41 Claims. (Cl. 1-3)

This invention relates to an improvement in stapling devices of the type employed in offices for fastening together papers or the like.

The stapling device is of the type which has a base supporting an anvil provided with camming slots designed to appropriately bend the legs of the staple. A staple carrying arm is mounted on the base and has means providing a magazine for the staples and also means supporting a staple driving tool effective, when operated, to eject a staple from the magazine and to coat with the anvil in effecting the stapling action.

Among the objects of the present invention are to provide an improved anvil construction and mounting to facilitate the bending of the staples in a variety of ways; to improve the mounting of the staple carrying arm on the base; to provide an improved arrangement for feeding or pushing the staples through the magazine which has the advantage, in particular, of facilitating loading of the magazine; and to provide for the mounting of the staple driving tool and its actuating plunger in a novel manner so as to render access to the staples more convenient.

Another object of the invention is to provide a stapling device having these advantages and capacities and which is simple and durable in construction, reliable and effective in operation and easy and comparatively inexpensive to manufacture.

Other objects and advantages reside in certain novel features of the construction, arrangement and combination of parts which will be herein-after more fully described and particularly pointed out in the appended claims, reference being had to the accompanying drawings forming a part of this specification, and in which:

Figure 1 is a view in side elevation showing a stapling device embodying the present invention, parts being broken away and shown in longitudinal vertical section for the sake of illustration;

Figure 2 is a view in transverse vertical section taken on line 2-2 of Figure 1;

Figure 3 is a view in horizontal section taken on line 3-3 of Figure 1;

Figure 4 is a plan view of the base with the anvil and staple arm mounting thereon, the staple carrying arm and parts associated therewith being removed for the sake of illustration;

Figure 5 is a fragmentary view in side elevation illustrating the construction of the forward end of the staple carrying arm, parts being broken away and portions being shown in section for the sake of illustration;

Figure 6 is a view in horizontal section taken on line 6-6 of Figure 5;

Figure 7 is a view in horizontal section taken on line 7-7 of Figure 5;

Figure 8 is a fragmentary view in vertical section taken on line 8-8 of Figure 4;

Figure 9 is a group view in elevation showing different ways of bending the staples;

Figure 10 is a view in vertical section taken on line 10-10 of Figure 11;

Figure 11 is a fragmentary view partly in side elevation and partly in vertical section showing a modified means for feeding or pushing the staples through the magazine;

Figure 12 is a fragmentary view showing the construction of the lower end of the staple driving tool;

Figure 13 is a group view showing in top plan and in edge elevation one construction of the connecting bar employed in the spring connection between the staple carrying arm and the base;

Figure 14 is a group view showing in front and side elevation the structure providing the lower abutment for the plunger spring;

Figure 15 is a fragmentary view partly in section and partly in elevation and showing on an enlarged scale the mounting of the detent of the full stroke insuring means; and

Figure 16 is a fragmentary view partly in side elevation and partly in longitudinal vertical section and illustrating the means employed for preventing distortion of the body portions of the staples during the driving and clinching thereof.

Referring to the drawings, it will be seen that the stapling device comprises generally a base 1 on which an anvil 2 is secured. At the end of the base opposite the anvil a mounting designated generally at 3 is provided for the beam or staple carrying arm designated generally at 4. The staple carrying arm is constructed to provide a magazine designated generally at 5 for the staples S. The end of the arm overlying the anvil 2 is provided with a main housing 6 constructed to provide a support and guiding means for the staple driving tool designated generally at 7 and its actuating plunger 8.

The base 1 consists of a metallic plate-like portion 10 of inverted dished form, the marginal edges of which are received within and confined by the flange 11 of a bottom 12 of cushioning material.

The anvil 2 comprises a plate-like member 13 of approximately triangular form. Camming grooves 14, 15 and 16 are provided in the upper surface of the anvil and are of different shape or

design so that when one camming groove is utilized the staple will be bent as indicated at 17 in Figure 9. When another is utilized the staple will be bent as indicated at 18 and 18' in Figure 9 5 and when the third camming groove is utilized the staple will be bent as indicated at 19 and 19' in Figure 9.

To provide for and facilitate the selective use of these camming grooves, one end of the anvil 10 is provided with a stud 20 which is riveted thereto and projects downwardly into a slot 21 formed in the metal plate 10 of the base. The stud 20 has a U-shaped spring 22 suitably fastened thereto. The ends of the spring project beyond the 15 slot 21 and are tensioned to bear against the underside of the plate 10 of the base in such manner as to hold the anvil firmly against the base. The intermediate portion of the anvil plate 13 is provided with a slot 23 angled or shaped 20 as shown. A headed rivet or fastening member 24 is secured to the base plate 10 and has its head overlapping the margins of the slot 23, the shank of the rivet or stud being a sliding fit in the slot 23. The forward end of the anvil plate is provided with a reduced flange 25 which is overlapped 25 by a holding tongue 26 struck up from the base plate 10. With this construction the anvil plate may be shifted transversely and longitudinally to bring any particular one of the camming slots 30 into cooperative relation with the driving tool of the stapling device. To maintain the selected slot in operative relation to the staple driving tool, the underside of the plate is provided with spaced recesses 27, 28 and 29, with which a ball or detent 35 30 is selectively engageable. The ball 30 is pressed upwardly by a spring 31 through an opening 32 in the base plate 10 and snapping into the recesses 27, 28 or 29 which is aligned therewith. An insert 33 is interposed between the cushioning 40 bottom 12 and the portion of the plate 10 which underlies the camming slots of the anvil to render the anvil rigid and preclude flexure. In lieu of an insert, a structure corresponding thereto and integral with the bottom 12 may be employed, if 45 desired.

The action of the camming slot 14 in forming the hook 19 on the staple is enhanced by means of a flat spring strip 34, a portion of which is riveted as at 35 to the anvil plate 13 and a portion of 50 which overlies the hooked or curved portion 19^a of the camming slot 14.

The mounting for the staple carrying arm consists of an inverted U-shaped bracket 36, the legs of which are riveted as at 37 to the base plate 10. 55

The staple carrying arm comprises an inverted channel-shaped core 38 and a single strip of sheet metal folded about the core 38 from one end thereof, as clearly shown in Fig. 6. Elongated portions of the sheet lie along the opposite sides 60 of the core 38 and provide side plates 39. The upper edges of the side plates are formed with inturned flanges 39'. The central portion of the sheet (connecting portion of the elongated portions) lies adjacent the said one end of the core 65 38 and defines a front wall 71, for purposes later to be described. Other portions of the sheet connected to the elongated portions and central portion define opposite walls 55 of the main housing 6 as will also be further described. The side 70 members of the core 38 have outwardly offset portions 40 which engage the side plates to spaced portions of said side plates from portions of the core and thereby define the magazine 5 for the staples. Rivets 41 secure the side plates 39 to the core 38. Obviously the side plates may be

secured to the core 38 by spot welding or in any other suitable manner.

The core 38 and side plates 39 overlap the mounting bracket 36 (Figures 1 and 2) and are pivotally connected thereto by means of a pivot pin 42. The portions of the side plates 39 adjacent the mounting 36 have integral extensions or arms 43 which project down through slots 44 in the base plate 10 into the space 45 formed between the base plate 10 and the bottom 10 12. The lower ends of these extensions or arms 43 are notched as at 46, the notches 46 providing seats for a cross bar 47 which extends transversely between the arms or extensions 43 and which is connected to one end of a retractile coil 15 spring 48, the other end of the spring being anchored to a lug 49 struck down from the base plate 10. The action of the spring 48 is to yieldably hold the staple carrying arm 4 in spaced relation to the anvil and thus permit of convenient insertion of the papers to be stapled in between the arm and the anvil. However, the spring 48 readily yields to allow the arm 4 to swing downwardly toward the anvil when the plunger which actuates the driving tool is depressed. In order to limit or fix the distance that the staple carrying arm 4 is manually spaced from the anvil, notched stops 51 are secured to and depend from the base plate 10 and engage the cross bar 47 to limit the extent which it may move to the left as viewed in Figure 1 and consequently limit the extent to which the staple carrying arm is swung away from the anvil under the influence of spring 48. However, the arm 4 may be swung further away from the anvil by hand, 35 the notched lower ends of the extensions 43 merely swinging away from the bar 47 which at such time is held stationary by virtue of its engagement with the notched stops 51. Slots 44 are of sufficient length to allow the desired manual 40 movement of the arm 4. As soon as the operator releases the arm 4 it swings by gravity back toward the anvil until its extension 43 again engages the bar 47.

If desired, the bar 47 may be constructed as 45 shown in Figure 13 wherein it is made up of two plate-like sections securely fastened together and formed with bearings 47^a receiving adjustable screws 47^b positioned to engage the lower ends of the extensions 43. The adjustment of the screws 50 47^b determines the distance the arm 4 is spaced from the anvil. Preferably the screws 47^b are a tight friction fit in the bearing 47^a so as to be held in any adjustment. In this construction the plates making up the bar 47 may have aligned 55 notches 47^c adjacent the ends of the bar and positioned and designed to interfit with the notches of the stops 51 and thereby insure a positive stop structure.

The main housing 6 has side walls 55 formed as 60 integral extensions of the side plates 39, there being curved connecting portions 56 between these side walls and the side plates 39, as illustrated in Figure 7. The upper portions of the side walls 55 are connected by a front portion 57 but below 65 this front portion 57 the front structure of the housing 6 consists merely of inturned flanges 58 formed integral with the forward edges of the side walls. The upper portion of the housing at the rear thereof is enclosed by a closure plate 59 70 having ears 60 overlapping the side walls 55 and being secured in position by a rivet 61.

The plunger 8 which actuates the driving tool has an upper section 62, a lower section 63 and an intermediate section 64 all formed of a single 75

piece of metal. The upper end of the upper section 62 is of complete tubular formation but below this upper end portion, the front of the upper section is cut away as shown. This provides a stop shoulder 62^a engageable with the upper edge of the front portion or wall 57 of the housing to limit the downward movement of the plunger. A cap or head 68 is fastened in any suitable way to the upper end of the upper section 62 to facilitate operation of the plunger. The intermediate section 64 is also of complete tubular formation and is shaped in cross section as shown in Figure 3. The upper edge of the front part of this intermediate section 64 provides a stop shoulder 64^a engageable with the lower edge of the front wall 57 of the housing to limit the upward movement of the plunger. The lower section 63 of the plunger is closed at the front but open at the rear and has marginal flanges 66 along its edges, the front faces of which are overlapped and engaged by the flanges 58 of the housing and the rear faces of which ride on bearing or guide projections 69 pressed out of the upper portion of the front wall member 71 which is integral with and extends transversely between the forward ends of the side plates 38.

The staple driving tool 7 has its lower or driving blade portion wider than its upper attaching or shank portion and at the juncture of the wide blade portion and narrow shank portion shoulders 7^a are formed. In the assembly the narrow shank portion of the driving tool is fitted up in the intermediate section 64 and upper section 62 of the plunger and is held flatly engaged with the inner faces of the rear walls of these sections by a rivet 65, the shoulder 7^a of the tool firmly abutting against the lower end of the intermediate section whereby the driving tool is positively backed up. This is especially advantageous as it provides the positive interconnection between the plunger and the driving tool so desirable to take care of the strains and stresses set up during the staple driving and clinching operations. The wide driving blade portion of the tool 7 travels in a guide-way 70, the upper portion of which is defined by the front wall 71 and the forward ends of the curved connecting portions 56, the latter being properly spaced from the wall 71 to effect this backing up or guiding of the driving tool and the lower portion of which guide is defined by the same wall 71 and the forward end of the core 38.

Integral with the wall member 71 and extending upwardly therefrom is a bracket 72 which provides an abutment for the lower end of a spring 74. The spring 74 extends up through the plunger and at its upper end encircles the centering pin 75 carried by the cap 68, the extreme upper end of the spring abutting the underside of the cap. The spring is tensioned to urge the plunger to its uppermost position but when the cap 68 is pushed downwardly the spring 74 is compressed to permit of downward movement of the plunger and staple driving tool. To complete the guiding of the plunger a guide roller 76 is provided and is mounted for rotation on the rivet 61 and bears against the flat back of the intermediate section 64 and upper section 62 of the plunger.

Means is provided for preventing return movement of the plunger to its uppermost position unless it has completed a full downward stroke and this means consists of a row of teeth 77 provided on the back of the upper portion of the plunger and cooperable with a detent 78 rotatably mount-

ed on a spacing collar 81^a provided on the rivet 61 between the adjacent end of the roller 76 and the adjacent side wall 55 of the housing. The detent 78 is influenced by a spring 79 to a position wherein its projection 80 is horizontally disposed. When the plunger is elevated the projection 80 is positioned below the row of teeth 77. As soon, however, as the plunger is slightly depressed the teeth 77 displace the projection 80, against the action of its spring, to a position wherein it declines downwardly and towards the teeth and hence is effective to prevent upward movement of the plunger although freely permitting downward movement. When the plunger has been completely depressed or has been moved downwardly through a complete down-stroke the upper ends of the row of teeth 77 pass below the projection 80 and the spring 79 returns the projection to its horizontal position, in which position it plays freely over the teeth 77 during the return movement of the plunger. The detent acts in a similar manner to prevent a down stroke until after the plunger has been fully elevated.

Means is provided for preventing deformation of the body portions of the staples as they are being driven by the staple driving tool and consist of a supporting member 81 pivotally mounted by means of a pin 82 on the side members of the core 38. The member 81 ordinarily occupies the position shown in dotted lines in Figure 1 where- in it is held against a stop pin 81^a under the influence of a spring 85, one end of which is anchored as at 86 to a lug struck from one of the side members of the core 38 and the other end of which is connected as at 87 to an arm integral with the member 81.

The supporting member 81 is provided at its forward end with an upper narrow tooth 84 and a lower and somewhat wider tooth 83, the teeth being separate by a slot 83^a designed to have a gauge fit over the body portion of a staple. When a staple is driven down through the guide-way 70 its body portion clears or passes freely by the upper tooth 84 but engages the tooth 83 which projects into the guide-way. As the staple continues to descend under the influence of the driving tool, the supporting member is swung about its pin 82 and the upper tooth 84 overlaps the body portion of the staple so that the body portion of the staple is now firmly held and supported by the teeth 83 and 84. The supporting action becomes effective before the legs of the staple contact the material and remains effective during the driving of the staple into the material and until the final phases of the driving and clinching when the supporting member releases and clears the staple to allow it to be fully and completely driven and clinched without interference by the supporting member. In such final phases of the stapling action the supporting member has swung on its pin 82 until the tooth 83 has moved out of the path of movement of the body portion of the staple. Upon return of the driver 7 to its upward position the wider portion of the tooth 83 engages the underside of the driver 7 and the member 81 rides along with the driver until restored to its upward position against the stop pin 81^a. The tooth 83 is also made wider than the tooth 84 so if the plunger is operated downward and no staples are in the stapling machine, the driver will contact this wider portion of tooth 83 and carry the member 81 downward allowing the tooth 84 to swing into the clearance 7' of the driver 7 (Figure 12), the same as it does if a staple were beneath the driver. If the tooth 83

were allowed to enter the clearance slot 7' the tooth 84 would wedge against the driver and jam the machine.

Means is provided for pushing or feeding the staples through the magazine and may consist of a follower or pusher 90 shaped to conform to and slide through the magazine and having its body portion raised as at 91 and riveted or otherwise suitably attached to a finger piece 93. The finger piece has transverse members 94 which are slotted to receive a mounting bar 95, the finger piece and follower being freely slideable along the mounting bar 95. The forward end of the mounting bar 95 is pivotally connected as at 96 with the side walls 55 of the main housing 6. The rearward end of this mounting bar is curved back upon itself as at 97 and this rear end portion carries an expansible coil spring 98, one end of which engages a fixed collar or abutment 99 pinned or otherwise secured on the mounting bar, and the other end of which engages one of the transverse members 94 of the finger piece. The spring 98 is tensioned to exert a push on the finger piece and consequently on the follower 90 thereby effecting feeding of the staples through the magazine. The curved form of the bar allows of the use of an appropriately long spring in a desirably compact construction.

When the magazine is to be loaded, the operator grasps the finger piece 93 and retracts it back along the bar 95 against the action of the spring 98. The rear transverse member 94 of the finger piece snaps into engagement with the hook 100 of a latch member 101 pivotally mounted on the curved end of the mounting bar and biased by its weight into latching position. When the finger piece is so latched the follower is moved back to a position where it is rearwardly of the side plates 39 of the magazine. Consequently it may freely move upwardly with the bar 95, when the bar is raised for the purpose of affording free and easy access to the magazine for loading the same with staples or for other purposes.

A modified form of staple feeding means is shown in Figures 10 and 11. In the modified form a pivoted mounting bar designated at 95' is provided and corresponds to the bar 95. A follower designated at 90' is also provided and corresponds to the follower 90. In lieu of the finger piece 93 a housing structure 105 is provided and has its base riveted as at 106 to the follower and has a longitudinal opening extending therethrough to receive the mounting bar 95'. The upper surface of the bar 95' is formed with a rack 107, with which a pinion 108 mounted for rotation within the housing meshes. The pinion 108 meshes also with a gear wheel 109 secured to and rotated with a shaft 110. The shaft 110 is driven by a spring motor. For example, it may be connected to one end of a coil spring 111 and the opposite end of the spring is anchored as at 112 on the housing. The arrangement is such that the spring is wound by a movement of the housing rearwardly on the bar 95' and its tendency to unwind results in the application of driving torque to the shaft 110, the gear wheel 109 and the pinion 108 whenever there is occasion for feeding. As the gear wheel 109 rotates under the influence of the spring it rolls along the rack 107 formed on the upper part of the bar 95' and consequently pushes the housing 111 and the follower 90' to the left as viewed in Figure 11.

In operation, the papers to be fixed together or stapled are placed on the anvil beneath the staple carrying arm. Previously, the anvil has been ad-

justed to bring the desired camming groove into operative position. The person using the device then presses down on the cap or head 68. This causes the staple driving tool to move downwardly and engage and drive the staple which lies in its path of movement. Under the influence of the driving tool and of the anvil the staple penetrates the papers and is properly bent or shaped. During the driving of the staple its body portion is held against bending in the manner pointed out.

In the event a crooked or bent staple is advanced through the guide-way 70 it is straightened unless too badly bent or deformed. In the latter event it is severed into pieces and is ejected from the machine. For this purpose the forward ends of the sides of the core are offset or pressed outwardly against the inner faces of the side plates 39 as indicated at 40' in Figures 5 and 6. These offset portions 40' are cut away on an incline as at 115 to provide inclined camming surfaces, the lower edges of which are effective as cutting edges. Ordinarily the bent leg of a staple striking the inclined surfaces of the cut-outs 115 will be bent back to proper shape and at the same time properly positioned in the guideway 70 but if the staple is too badly bent, as indicated at S' in Figure 5, the driver will coat with cutting edges at the lower ends of the inclines to sever the bent staple into pieces. Adjacent the cut-out 115 the side plates 39 are formed with the openings 116 through which the severed legs of such a badly bent staple will fall. The body portions of such severed staples are driven out through the guide-way 70.

A somewhat special action is involved in bending a staple into the shape designated at 19, 19' in Figure 9. To effect such bending the staple driving tool coats with cam slot 14. The slot 14 is designed to bend the legs of the staple outwardly after these legs have been driven through the material and into the slot. One leg of the staple remains straight when viewed from above. The slot in which this leg enters has a square shoulder at its outer end as is clearly shown in Figure 8. The purpose of this shoulder is to prevent the body portion of the staple from shifting toward the straight leg side under the influence of the reaction set up by the special bending action of the other leg. The leg to be hooked slides under the flexible member 34 and into the hooked end 19a (when viewed from above) of the slot 14, as is shown in Figure 4. The hooked end of the slot 14 imparts to this leg a hooked shape like that shown in Figure 9. An additional strain is set up in bending the hooked leg, especially toward the latter part of the downward movement of the driving tool, which has a tendency to cause the staple to shift toward the straight leg side. As explained above this is offset by the shoulder at the end of the straight leg slot. It is to be understood that the same sized staple is utilized in this particular action as is used when forming the staple as viewed in 17, 17' and 18, 18' of Figure 9. It is only the leg portions of the staple after entering through the material which are formed as described. The member 34 in cooperation with presser flange 39a (Figures 7 and 8) carried by the side plates 39 acts as a cover plate for the hooked end of the camming slot and prevents the staple leg from over-riding the slot during the forming action. After the staple has been completely driven and formed and the staple arm returned to its upward position, the member 34 will readily release 75

the staple from the slot by pulling forward and upward on the material.

While I have shown and described constructions in which the invention may be embodied, it is to be understood that these constructions have been selected merely for the purpose of illustration and various changes may be made in the size, shape and arrangement of the parts without departing from the spirit of the invention or the scope of the subjoined claims.

The invention claimed is:

1. A stapling device comprising a base, an anvil thereon, an arm mounted on said base and having means providing a magazine for staples, a housing carried by said arm, a staple driving tool slideable in said housing, a plunger disposed forwardly in said housing, said tool having a portion enclosed by said plunger and connected thereto and a spring in said plunger disposed forwardly of said driving tool for urging said plunger and driving tool to elevated position.

2. A stapling device comprising a base, an anvil thereon, an arm mounted on said base and having means providing a magazine for staples, a housing carried by said arm, a staple driving tool slideable in said housing, a plunger disposed forwardly in said housing and connected to said tool for operating the same, a spring disposed in said plunger forwardly of said driving tool for urging said plunger and driving tool to elevated position, a follower for feeding the staples through said magazine, a bar pivoted to the housing adjacent said plunger and along which the follower is slideable and spring means for urging the follower along said bar.

3. A stapling device comprising a base, an anvil thereon, an arm mounted on said base and having means providing a magazine for staples, a housing carried by said arm, a staple driving tool slideable in said housing, a plunger disposed forwardly of said housing and connected to said tool for operating the same, a spring disposed forwardly of the plunger for urging said plunger and driving tool to elevated position, a follower for feeding the staples through said magazine, a bar pivoted to the housing and along which the follower is slideable, and spring means for urging the follower along said bar in combination with means for latching the follower in retracted position and out of the magazine whereby it may be swung with the bar away from the magazine to facilitate access thereto.

4. In a stapling device of the type having a magazine for the staples, a follower for advancing the staples through the magazine, a pivotally mounted bar interconnected with the follower and along which the follower is slideable, said bar having one end reversely bent, a spring encircling said reversely bent end and having one end engaging the follower, and an abutment on the bar for the other end of said spring.

5. A stapling device comprising a base, an anvil thereon, an arm having means providing a magazine for the staples, a staple driving tool carried by said arm, means pivotally mounting the arm on the base, and means for yieldably urging the arm away from the base including extensions integral with and depending downwardly from the arm, a cross bar engaging said extensions, and a spring interconnecting the cross bar and the base.

6. A stapling device comprising a base, an arm pivotally mounted on the base and having means providing a magazine for the staples, a staple driving tool mounted on said arm, an anvil shift-

ably mounted on the base and having a plurality of sets of camming slots selectively cooperable with the staple driving tool depending upon the position of the anvil, means controlling the shifting movement of the anvil including a stud connected to the anvil, said base having a longitudinal slot cooperable with such stud and a second stud connected to the base, said anvil having an angular slot cooperable with said second stud, and means for releasably securing the anvil in adjusted position.

7. A stapling device comprising a base, an arm pivotally mounted on the base and having means providing a magazine for the staples, a staple driving tool mounted on said arm, an anvil having a plurality of sets of camming slots selectively cooperable with said tool depending upon the position of the anvil, means interconnecting the anvil and the base whereby the anvil is slideable longitudinally and transversely with respect to the base, and means for releasably securing the anvil in any selected adjustment.

8. In a stapling machine, an anvil having a camming slot, one end of said slot being curved to form a hook-shaped outline and a yieldable holding element immediately overlying and covering said end.

9. A stapling device comprising a staple carrying arm, a housing thereon, a staple driving tool slidably mounted in said housing, a hollow plunger connected to said staple driving tool and arranged forwardly in said housing, said plunger having upper and lower portions and an intermediate portion, the upper portion opening forwardly and the lower portion opening rearwardly, a spring for elevating the plunger and extending through the portions thereof, and means on the housing for guiding the plunger.

10. A stapling device having means for driving the staple, and means for preventing deformation of the body portions of the staples during driving and comprising a shiftably mounted supporting member having a slot receiving and supporting the body portion of the staple during the staple driving action, said member being shiftable out of the way of the staple in the final phases of the driving action.

11. In a stapling device, staple driving means comprising a hollow reciprocal plunger, a housing for said plunger, a driving tool mounted in said housing, and spring means for urging said plunger in elevated position, said driving tool having a narrow portion enclosed by said plunger, said narrow portion and said driving tool defining a shoulder abutting said plunger to form a supporting means for said driver during its staple driving operation.

12. In a stapling device, staple driving means comprising a hollow reciprocal plunger, a housing forming guiding means for said plunger, a driving tool attached to said plunger, said plunger having a portion of its lower rear section removed, said driving tool closing said portion and a spring for elevating said plunger mounted between said driving tool and the front face of said plunger.

13. In a stapling device, staple driving means comprising a hollow reciprocal plunger, a housing providing guiding means for said plunger, said plunger having a top portion and an intermediate section of full enclosing cross section and upper and lower portions of part enclosing cross section, a cap piece mounted upon said top portion and a driving tool connected to said plunger, said housing coating with said top por-

- tion and said intermediate section to limit the movement of said plunger.
14. In a stapling device, staple driving means comprising a hollow reciprocal plunger, a housing for said plunger, a spring within said plunger to retain it in raised position, said plunger having a cross section shaped with side and rear sections forming a U-shape, a front section having a portion approximately at right angles to said side sections and an outwardly rounded portion forming a clearance space for said spring and means on said housing coacting with said side and rear sections and said first-named portion of said front section for guiding said plunger.
15. In a stapling device having a reciprocal plunger, a housing providing guiding means for said plunger, a full stroke mechanism comprising a rack carried by said plunger and a detent carried by said housing, and a roller mounted within said housing forming one of the guides for said plunger, said roller cooperating with said housing to guide said detent in alignment with said rack.
16. In a stapling device having a reciprocal plunger, a housing for said plunger, said housing having means for guiding said plunger during its reciprocation and including a single roller rotatably supported within said housing.
17. In a stapling device, a base having an anvil, a beam magazine movably mounted to said base, said magazine comprising a core forming a staple track and a one-piece sheet metal member formed about said core to guide the staples thereon, said member having extension members extending through said base and spring operated means cooperating with said extension members to elevate said beam magazine in a spaced relation to said anvil.
18. In a stapling device, a base having an anvil, a beam magazine movably mounted to said base, said magazine comprising a core forming a staple track and side plates for guiding the staples on said track, said side plates having extension members, spring operated means cooperating with said extension members to elevate said beam magazine in relation to said anvil and adjustable means cooperable with said extension members to vary the relation of said beam magazine to said anvil.
19. In a stapling machine of the type specified, a base having an anvil, a staple carrying arm comprising an inverted-channel shaped core and staple retaining means thereon to provide a magazine for staples, a staple driving means carried by said arm and a mounting bracket for said arm secured to said base, said core overlapping said bracket and pivotally connected thereto whereby said bracket and core coact to align said anvil and said driving means.
20. In a stapling device having a staple driving tool and a beam magazine for staples comprising an inverted U-shaped core forming a staple track and side plates, and a housing for said staple driving tool carried by said magazine, said core having the forward ends of its sides cut away on an incline to provide cutting edges cooperating with said driving tool to sever crooked or misplaced staples on said track and openings in said side plates for discharging severed staple sections.
21. In a stapling device, a base, an anvil on said base, staple driving means carried by said base, said anvil having a plurality of staple deforming cavities and means for locking said anvil in relative positions on said base, said anvil being movable longitudinally and transversely to align

said deforming cavities with said staple driving means.

22. In a stapling device, a base, an anvil having a plurality of deforming cavities on said base, staple driving means carried by said base, said anvil being shiftable longitudinally and transversely to align said deforming cavities with said staple driving means and a camming arrangement for controlling the longitudinal and transverse movement of said anvil.

23. In a stapling device having staple driving means, a base, a shiftable anvil having a plurality of staple deforming cavities mounted on said base, said anvil having a slidable pivotal connection at one end and an overlying member providing guiding means for another end whereby said anvil is shiftably secured to said base.

24. In a stapling device, a base, a shiftable anvil having a plurality of staple deforming cavities mounted flatwise on said base, staple driving means carried by said base, means shifting said anvil longitudinally when said anvil is shifted transversely to align said cavities with said driving means and locking means between said base and said anvil comprising a spring-operated ball carried by one of said members and recesses carried by the other of said members to releasably lock said anvil in relation to said staple driving means.

25. In a stapling device having staple driving means comprising a plunger and a staple driving tool, a housing for said plunger and said tool, an ejection chute through which the staples are driven, supporting means engageable with the top and bottom of the body portion of a staple movably mounted and extending into said ejection chute and a cut-out portion in said driving tool to accommodate said supporting means.

26. In a staple driving device having a staple driving tool, supporting means to prevent the bridge portions of staples from buckling as they are being driven into material comprising a movable member encasing the body portion of a staple while being driven and a spring support for said member, said driving tool having a clearance space to accommodate said member.

27. In a staple driving device having a staple driving tool, supporting means providing a toothed structure having a gauge fit over the body portion of staples being driven to prevent the bridge of staples from buckling as they are driven into material, one of said teeth of said supporting means being wider than its opposing tooth.

28. In a stapling machine of the type specified, a staple magazine, an ejection chute through which staples are driven from said magazine, a housing positioned on said magazine over said ejection chute, a plunger reciprocally carried by said housing, a staple driving tool carried by said plunger and operable to drive staples through said chute and a member extending upwardly from said ejection chute and into said housing, said member being spaced from said housing and forming a rear guide for said plunger and a forward guide for said tool.

29. In a stapling machine of the type specified, a staple magazine consisting of a core provided with top and side staple guiding means providing an enclosed run-way for staples, said magazine being open at its ends for the entrance and discharge of staples, a bar pivotally mounted outside of said magazine, a follower slidably interconnected with said bar, said follower having a portion slidable within said magazine and on said core for advancing staples through said

magazine, and spring means acting between said follower and said bar whereby said portion is urged to advance staples.

30. In a stapling machine of the type specified, a staple magazine consisting of a core provided with top and side staple guiding means providing an enclosed run-way for staples, said magazine being open at its ends for the entrance and discharge of staples, a bar pivotally mounted outside of said magazine, a follower slidably interconnected with said bar, said follower having a portion slidable within said magazine and on said core for advancing staples through said magazine, spring means acting between said follower and said bar whereby said portion is urged to advance staples and latch means on said bar engageable with said follower for holding the same in retracted position and out of said magazine whereby said follower and bar may be swung away from said magazine to facilitate loading thereof.

31. In a stapling machine of the type specified, a staple magazine consisting of a core provided with top and side staple guiding means providing an enclosed run-way for staples, said magazine being open at its ends for the entrance and discharge of staples, a bar pivotally mounted outside of said magazine, a follower slidably interconnected with said bar, said follower having a portion slidable within said magazine and on said core for advancing staples through said magazine, and spring means coiled about said bar and having one end engaging the follower and the other end engaging the end of said bar opposite said pivotal mounting.

32. In a stapling machine of the type specified, a staple magazine consisting of a core provided with top and side staple guiding means providing an enclosed run-way for staples, said magazine being open at its ends for the entrance and discharge of staples, a bar pivotally mounted outside of said magazine, said bar having one end reversely bent and providing an abutment, a follower slidably interconnected with said bar and having a portion slidable within said magazine and on said core, and a spring encircling said reversely bent end and having one end engaging said follower and the other end engaging said abutment.

33. In a stapling machine of the type specified, a staple magazine consisting of a core provided with top and side staple guiding means providing an enclosed run-way for staples, said magazine being open at its ends for the entrance and discharge of staples, a bar pivotally mounted outside of said magazine, a follower slidably interconnected with said bar, said follower having a portion slidable within said magazine and on said core for advancing staples through said magazine, and a spring propelled motor carried by said follower and acting on said bar for advancing said portion through said magazine.

34. In a machine of the type specified, a core, a single strip of sheet metal folded about said core from one end thereof, elongated portions of said strip coacting with the sides of said core to define a magazine for staples, the connecting portion of said elongated portions being spaced from and coacting with the said one end of said core to form an ejection guideway for staples being driven from said magazine and staple driving means positioned on said magazine, said means being guided by said ejection guideway and operable to drive staples from said magazine.

35. In a machine of the type specified, a core,

a single strip of sheet metal folded about said core from one end thereof, elongated portions of said strip coacting with the sides of said core to define a magazine for staples, the connecting portion of said elongated portions being spaced from and coacting with the said one end of said core to form an ejection guideway for staples being driven from said magazine, still other portions of said strip being integrally connected with said elongated portions and forming the walls of a main housing and staple driving means carried by said main housing, said means being guided by said ejection guideway and operable to drive staples from said magazine.

36. In a machine of the type specified, a core, a single strip of sheet metal folded about said core from one end thereof, elongated portions of said strip coacting with the sides of said core to define a magazine for staples, the connecting portion of said elongated portions being spaced from and coacting with the said one end of said core to form an ejection guideway for staples being driven from said magazine, said connecting portion having an upwardly projecting bracket integrally formed thereon, a staple driving tool operable in said ejection guideway for driving staples from said magazine, a plunger for operating said tool and a spring for urging said plunger to elevated position, said spring having one end guided and carried by said bracket and the other end engaging said plunger.

37. In a machine of the type specified, a core upon which staples ride in straddle fashion, a single strip of sheet metal folded about said core from one end thereof, elongated portions of said strip coacting with said core to define side plates guiding staples on said core, said plates having inturned flanges providing a top guide for staples on said core, the connecting portion of said elongated portions being adjacent and spaced from the said one end of said core and coacting therewith to define an ejection guideway for staples being driven from said core, still other portions of said strip forming the walls of a main housing, said walls being integrally connected with said flanges for a portion of the length thereof by curved portions, said curved portions being spaced from and coacting with said connecting portion to form a tool guide, a staple driving tool operable in said tool guide to drive staples from said core out through said ejection guideway and a plunger operably supported by said main housing and secured to said tool for operating the same.

38. In a machine of the type specified, a core, a single strip of sheet metal folded about said core from one end thereof, elongated portions on said strip coacting with said core to form a magazine for staples, the connecting portion of said elongated portions being adjacent and spaced from the said one end of said core and coacting therewith to form an ejection chute for staples being driven from said magazine, still other portions of said strip extend upwardly from said elongated portions and form the walls of a main housing positioned above said ejection chute, a staple driving tool operable to drive staples from said magazine and out through said ejection chute and a plunger for operating said tool, said plunger being slidably guided by the inner surfaces of said walls of the main housing and by the outer surface of said connecting portion.

39. In a stapling machine of the type specified, a staple magazine consisting of a core provided

- with top and side staple guiding means providing an enclosed run-way for staples, said magazine being open at its ends for the entrance and discharge of staples, a bar pivotally mounted outside of said magazine, a follower slidably interconnected with said bar, said follower having a portion slidable within said magazine and on said core for advancing staples through said magazine, said bar being provided with a rack on one face thereof and a spring drum intergeared with the rack and connected with said follower for advancing the follower through the magazine.
- 5 5
- 10 40. In a stapling machine of the type specified, a staple magazine consisting of a core provided with top and side staple guiding means providing an enclosed runway for staples, said magazine being open at its ends for the entrance and discharge of staples, a bar pivotally mounted out-

side of said magazine, a follower slidably interconnected with said bar, said follower having a portion slidable within said magazine and on said core for advancing staples through said magazine, said bar being provided with a rack on one face thereof and a spring drum intergeared with the rack and connected with said follower for advancing the follower through the magazine.

41. In a stapling machine having a staple driving means and a beam magazine, a core having 10 shoulders extending longitudinally thereof and defining a staple track, said core having projections at spaced intervals along the length thereof, and side plates mounted against said projections and in spaced relation to said track to guide the 15 staples thereon, said side plates and projections providing openings between said side plates and said core permitting discharge of foreign substance from said magazine.

WILLIAM G. PANKONIN. 20
